[57] CLAIM

The ornamental design for an irregularly shaped dice, as shown.

DESCRIPTION

FIG. 1 is a top, front, left side perspective view of an irregularly shaped dice showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a bottom view thereof;

FIG. 7 is a back elevational view thereof;

FIG. 8 is a top, front, left side perspective view of an alternate embodiment of FIG. 1;

FIG. 9 is a top plan view of FIG. 8;

FIG. 10 is a left side elevational view of FIG. 8;

FIG. 11 is a front elevational view of FIG. 8;

FIG. 12 is a right side elevational view of FIG. 8;

FIG. 13 is a bottom plan view of FIG. 8; and,

FIG. 14 is a rear elevational view of FIG. 8.

FIG. 2**FIG. 3****FIG. 4****FIG. 5****FIG. 6****FIG. 1****FIG. 7**

FIG. 9**FIG. 10****FIG. 11****FIG. 12****FIG. 8****FIG. 13****FIG. 14**
